UNITED STATES PATENT OFFICE.

HAROLD B. BARNES, OF DENVER, COLORADO.

COMBINED PENCIL-SHARPENER AND MANICURING DEVICE.

1,070,660.

Specification of Letters Patent. Patented Aug. 19, 1913.

Application filed October 30, 1909. Serial No. 525,518.

To all whom it may concern:

Be it known that I, HAROLD B. BARNES, a citizen of the United States, residing in the city and county of Denver and State of Colorado, have invented certain new and useful Improvements in Combined Pencil-
5 Sharpeners and Manicuring Devices, of which the following is a specification.

My invention relates to an improvement 10 in combined pencil sharpeners and manicure devices, and the object is to provide a device adapted to utilize the blades of the various types of safety razor, and it consists in a socket having a slotted side, the 15 cone adapted to receive and guide the pencil to be sharpened, in connection with two plates, one of which extends tangentially from the cone, starting from the slot, and the other a removable clamping plate, the 20 two being adapted to receive a thin blade between them and form a guard about the edges thereof, with means for retaining the blade in position between and within the 25 confines of the edges of the plates, and means for removably securing the clamping 30 plate in position.

My invention further consists in certain novel features of construction and combinations of parts, which will be hereinafter 35 described and pointed out in the claims.

In the accompanying drawings: Figure 1 is a view from one side; Fig. 2 is a view from one edge; and Fig. 3 from one end of the preferred form of device; Fig. 4 is a 40 view with the blade and clamping plate removed; Fig. 5 is a transverse section through one of the studs and through the blade; and Fig. 6 is a section through the manicuring portion.

In the preferred construction, 1 indicates a cone-shaped socket, the interior bore of which is designed to conform in pitch to the end of the pencil when sharpened. A 45 base plate 2 extends tangentially from the socket, and a slot 3 extends lengthwise the cone at the juncture of the cone and plate, this slot having two main functions, one as a space for the cutting edge of the blade, and the other to permit the ready escape of 50 the shavings from the pencil being sharpened. At the larger end of the socket the slot 3 is very narrow and the metal of the base forms a guard for the blade as at "a," so that the portion of the blade at this point 55 is protected and not exposed to wear due to the sharpening of the pencil. The inner

face of the plate may be flat or curved, in the drawings it is shown flat, and in the form illustrated the plate has a centrally located internally screw-threaded orifice 4 60 and is provided on either side of the orifice 4 with studs 5, 5. These studs enter the holes 6, 6 of the blade 7. The studs are sufficiently less in diameter than the holes to admit of the blade being adjusted toward 65 the pencil socket a limited distance to compensate for wear and sharpening.

A clamping plate 8 is adapted to fit the base plate 2 and the two receive the blade between them, and for this purpose, the 70 clamping plate is provided with recesses 9, 9, to receive the ends of the studs, thus assisting in centering the clamping plate, and it has a central orifice 10 adapted to register with the threaded orifice 4 in the 75 base plate, so that the screw 11 passing through the two orifices and the central orifice of the blade, is turned into the threads to hold the parts securely together. The size of the base and clamping plates is sufficient 80 so that they protrude beyond the outer edge of the blade to form a guard, whereas the length may just correspond to the blade, if desired.

Beveled notches 12, 12 are formed in the 85 outer edges of the base and clamping plates, so as to register with each other, their purpose being to expose a limited area of the outer edge of the blade, so that this portion may be used for manicuring purposes. The 90 outer edge of the clamping plate is preferably beveled throughout its length, although not necessarily, and its outer surface is knurled in the form of a file for filing the rough edge of the nails. It will be observed 95 that these notches 12, 12, are approximately the same distance from the central orifice 4 as the portion "a" is. There is a reason for this, which is that the portion of the blade which comes opposite the part "a" 100 of the base plate is not touched by the pencil and consequently does not become worn, so it is sharp and ready for use in manicuring when the blade is reversed, if a two-edged blade, as is contemplated by the invention.

From the foregoing, it will be seen that a provision is made for utilizing to good advantage an otherwise waste product, namely, razor blades having two cutting 110 edges, while at the same time taking advantage of a superior quality of steel which

will hold the sharp cutting edge for a more or less indefinite period. Again, it will be observed that in a blade of the type mentioned, in which both edges are sharp, both 5 edges may be utilized in a device of this character, as specified, one for pencil sharpening, and one for manicuring.

My invention applies equally well to other types of safety razor blades as previously set forth, and it is obvious with very 10 slight modifications might be so adapted.

More or less slight changes might be resorted to in the form and arrangement of the several parts described, in addition to 15 those specified, without departing from the spirit and scope of my invention, and hence, I do not wish to limit myself to the exact construction herein set forth, but:

Having fully described my invention, 20 what I desire to secure by Letters Patent, is:—

1. The combination with two plates, of a blade held between said plates, the relative width of plates and blade being such 25 that when one edge of the blade is exposed, the other is guarded and protected, the plates having correspondingly located beveled notches at one end in position to expose a small portion only of one edge of the blade 30 for manicuring purposes, one of said plates extending over a portion of the exposed cutting edge of the blade for preventing the guarded portion from being dulled, and said guarded portion of the blade adapted 35 to be exposed at the notches of the plates when the blade is reversed, and means adjacent the opposite and exposed edge of the blade for holding and guiding the pencil which that edge of the blade is intended to 40 sharpen.

2. The combination with two plates, of a reversible blade held between said plates, the relative width of plates and blade being

such that when one edge of the blade is exposed the other is guarded and protected, 45 the plates having correspondingly located beveled notches at one end in position to expose a small portion of one edge of the blade for manicuring purposes, an extension formed on one of the plates which extends 50 over a portion of the exposed cutting edge of the blade, and a socket mounted upon said plate and lying adjacent to the exposed edge of the blade for holding and guiding a pencil which that edge of the blade is intended 55 to sharpen, the portion of said blade guarded by the extension of one of the plates adapted to be exposed at the notches of the plates when the blade is reversed. 60

3. The combination with two plates, of a reversible blade held between said plates, the relative width of plates and blade being such that when one edge of the blade is exposed the other is guarded and protected, 65 the plates having correspondingly located beveled notches at one end in position to expose a small portion of one edge of the blade for manicuring purposes, and a slotted socket mounted upon one of the plates and 70 lying adjacent to the exposed edge of the blade for holding and guiding a pencil which that edge of the blade is intended to sharpen, said socket having one end of the slot closed for forming a guard for a portion 75 of the cutting edge of the exposed blade, said guarded portion of the blade adapted to be exposed at the notches of the plates when the blade is reversed.

In testimony whereof I affix my signature 80 in the presence of two witnesses.

HAROLD B. BARNES.
